UNITED STATES PATENT OFFICE.

WALTHER BEHM, OF NEW YORK, N. Y.

NOZZLE FOR VACUUM-CLEANERS.

1,013,364.

Specification of Letters Patent.

Patented Jan. 2, 1912.

Application filed February 15, 1911. Serial No. 608,831.

To all whom it may concern:

Be it known that I, WALTHER BEHM, a citizen of the German Empire, residing in New York, in the borough of Manhattan, county and State of New York, have invented certain new and useful Improvements in Nozzles for Vacuum-Cleaners, of which the following is a specification.

This invention relates to a suction nozzle 10 for vacuum cleaners which is easily operative and efficient in action without particular care as to the angle at which it is held to the carpet or other surface being cleaned.

The object of the invention is to provide a 15 nozzle of this character which is strong, durable and light and which will distribute the suction evenly from end to end of the contact part thereof.

In the accompanying drawings, Figure 1 20 is a perspective view, showing the nozzle in use. Fig. 2 is a longitudinal, vertical, sectional view of the same, and Figs. 3 and 4 are sectional views taken respectively on lines 3—3 and 4—4 of Fig. 2.

25 Similar letters of reference indicate corresponding parts throughout the several figures of the drawings.

Referring more particularly to the drawings, my improved nozzle 5 is shown applied 30 to the lower end of a suction conduit 6. This conduit may be a tubular handle of a power operated suction-cleaner or may be simply a hose connection, or it may be a direct connection with a hand-operated cleaner. The 35 nozzle may be connected to the conduit 6 in any approved manner, as for instance, by means of a bayonet-slot 7 provided in the end of the conduit 6 and in which engages a lug 8 on the stem 9 of the nozzle. The nozzle 40 comprises a longitudinal core 10 of approximately cylindrical shape and provided at its lower part with a downwardly opening longitudinal groove 11 extending to the lower face thereof. This groove is deepest at its center and tapers outwardly to the ends, and, if desired, may terminate short of the ends as shown. Around the core is placed a 45 sheet metal casing 12 firmly fitting thereon and curved at 15 around the lower edges of the slot 11 and clamped thereto. The ends of the core 10 are covered with an end piece 13 soldered or otherwise secured to the covering 12. The center of the core 11 is pro-

vided with an upwardly extending opening 14 communicating with the tubular stem 9 55 which in turn communicates with the conduit 6, as heretofore explained. Flanges 16 may be extended under the tip ends of the core at opposite ends of the slot, if desired, if the cores be not otherwise protected. 60

The curved portion of the covering 12 near both edges of the slot 11 serve as a contact surface for the nozzle and hold the slot 11 within operative distance of the surface being cleaned, so that, notwithstanding 65 whether the angle of the nozzle to the surface be that illustrated or not, the action of the nozzle is efficient at almost any angle at which it would likely be used.

The object of having the slot 11 tapered 70 from the center outward is that the suction from the stem 4 is distributed evenly from end to end of the slot 11 rather than being concentrated at the opening 14 as would be the case were the slot not tapered. 75

The cylindrical core 10 may be of any desired material, but I prefer to make it of some strong light weight wood, so that great strength is imparted to a nozzle without increasing its weight, so that the person using 80 the same will not be unnecessarily fatigued. By reason of the curved surfaces the carpet is saved from deterioration.

It is particularly understood that I may make various changes in the details of the 85 nozzle, without departing from the spirit and scope of the invention.

Having thus described my invention, I claim as new and desire to secure by Letters Patent:

1. A suction nozzle for a vacuum apparatus comprising a cylindrical solid core provided with a longitudinal groove open along its under side and with a transverse opening at its center connecting with said groove and a 95 cylindrical sheet metal casing inclosing said core and provided with a longitudinal slot on its lower side registering with said groove and with a central tube on its upper side opposite said opening for connection 100 with the vacuum apparatus.

2. A suction nozzle for a vacuum apparatus comprising a cylindrical solid core provided with a longitudinal groove open along its under side and tapered in depth toward 105 the outer ends and with a transverse opening

at its center connecting with said groove and a cylindrical sheet metal casing inclosing said core and provided with a longitudinal slot on its lower side registering with said groove and with a central tube on its upper side opposite said opening for connection with the vacuum apparatus.

In testimony, that I claim the foregoing as my invention, I have signed my name in presence of two subscribing witnesses.

WALTHER BEHM.
